UNITED STATES PATENT OFFICE.

PETER H. SEREFF, OF LIMA, OHIO.

INK-WELL.

1,242,991.

Specification of Letters Patent. Patented Oct. 16, 1917.

Application filed March 8, 1917. Serial No. 153,343.

To all whom it may concern:

Be it known that I, PETER H. SEREFF, a citizen of the United States, residing at Lima, in the county of Allen and State of Ohio, have invented certain new and useful Improvements in Ink-Wells, of which the following is a specification.

My invention relates to improvements in ink wells, having automatic means to feed the ink from the main reservoir or storage tank, to a point where the same may be conveniently applied to the pen.

An important object of the invention is to provide an ink well of the above mentioned character, having means to automatically seal the same to the exclusion of the atmosphere, thus preventing evaporation of the ink.

A further object of the invention is to provide an ink well of the above mentioned character, which is highly convenient in use, and so constructed that the pen point may be readily dipped into the ink, while the pen handle is held by the fingers in the usual position for writing.

A further object of the invention is to provide an ink well of the above mentioned character, having a low center of gravity, so that the same will not be readily upset.

A further object of the invention is to provide a device of the above mentioned character, which is simple in construction, inexpensive to manufacture, durable, and attractive in appearance.

Other objects and advantages of the invention will be apparent during the course of the following description.

In the accompanying drawings forming a part of this specification and in which like numerals are employed to designate like parts throughout the same,

Figure 1 is a side elevation of an ink well embodying my invention,

Fig. 2 is a plan view of the same,

Fig. 3 is a central vertical sectional view through the same, and,

Fig. 4 is a detail section taken on line 4—4 of Fig. 3.

In the drawings, wherein for the purpose of illustration is shown a preferred embodiment of my invention, the numeral 5 designates a main reservoir, which is preferably semi-spherical and is provided with a flat base 6, whereby the reservoir has a low center of gravity, and is not liable to be knocked

over or upset. The main reservoir is preferably formed of glass, while other suitable material may be employed.

The main reservoir 5 is provided upon one side and near its bottom with an opening 7, for receiving a tubular housing 8, which fits snugly within the opening to form a liquid tight joint. Any suitable means may be employed for effecting a proper union between the housing 8 and the main reservoir 5. The housing 8 projects into the main reservoir 5 for a substantial distance, and has its inner end formed open, such opening being normally closed by a head or end 9, forming a liquid tight joint with the housing. The lower portion or bottom of the housing 8 is provided with a recess or opening 10, extending between spaced tracks 11. The recess 10 is in communication with inverted V-shaped openings 12, in turn communicating with the interior of the main reservoir 5. The housing 8 is provided at its forward end with a spherically curved valve seat 13, which is suitably ground to receive a ball valve 14, and form an air tight joint therewith. The ball valve 14 travels upon the tracks 11, which are vertically inclined and extend downwardly toward the valve seat 13, thus causing the ball valve to automatically return to its seat. The ball valve 14 is inserted into the housing 8 by removing the end 9.

In the use of the device, the housing 8 is removed from the opening 7, and the main reservoir 5 partly or wholly filled with liquid ink. The housing 8 is then returned to the operative position within the opening 7. The device operating upon the principle of a barometer, a portion of the ink will pass from the main reservoir through the openings 12 and will be held within or adjacent the recess 10 of the housing 8, the level of the ink within the space 10 being automatically maintained constant. When the ball valve 14 is seated, the atmosphere is effectually excluded from the interior of the housing 8, thus preventing the evaporation of the ink being held within the recess 10. The operator may hold the pen handle between the fingers, in the usual position for writing, and press the pen point against the ball valve, which will move rearwardly along the inclined tracks 11, thus allowing the pen point to be immersed into the ink. When the pen is withdrawn the ball valve 14

will automatically return to its seat 13. As the level of the ink in the recess 10 is retained above the top of the openings 12, the housing 8 serves as a seal for the main reservoir 5, thus excluding the atmosphere therefrom when the ball valve is seated or unseated.

It is to be understood that the form of my invention herewith shown and described is 10 to be taken as a preferred example of the same, and that various changes in the shape, size, and arrangement of parts may be resorted to without departing from the spirit of the invention or the scope of the 15 subjoined claims.

Having thus described my invention, I claim:

1. An ink well of the character described, comprising a main reservoir, a housing connected with the main reservoir and provided in its lower portion with a recess having communication with the interior of the main reservoir, said housing being provided with an inclined guide-way and a valve seat at 25 the lower end of the guide-way, and a roll-

ing valve arranged to travel upon the guide-way and to contact with the valve seat.

2. An ink well of the character described, comprising a main reservoir provided near its bottom with an opening, a housing secured within the opening and projecting into the main reservoir, said housing having its outer end open, its inner end closed, and its bottom provided with an opening leading to the interior of the main reservoir, 30 said housing being further provided with inclined tracks extending downwardly toward the open end of the housing, said housing being provided at the lower ends of the tracks with a spherically curved valve seat, 35 and a ball valve mounted within the housing to travel upon the tracks and to contact with the valve seat.

In testimony whereof I affix my signature in presence of two witnesses.

PETER H. SEREFF.
